UNITED STATES PATENT OFFICE.

LEE W. BARBER AND EDWIN W. WEBB, OF CHICAGO, ILLINOIS, ASSIGNEES TO
STANDARD CAR TRUCK COMPANY, OF CHICAGO, ILLINOIS, A CORPORATION
OF NEW JERSEY.

SIDE BEARING.

Application filed June 6, 1921. Serial No. 475,395.

To all whom it may concern:

Be it known that we, LEE W. BARBER and EDWIN W. WEBB, citizens of the United States, residing at Chicago, in the county of Cook and State of Illinois, have invented certain new and useful Improvements in Side Bearings; and we do hereby declare the following to be a full, clear, and exact description of the invention, such as will enable others skilled in the art to which it appertains to make and use the same.

This invention relates to a bearing for railway cars and particularly to a side bearing adapted to be disposed between the truck and body bolsters of such a car.

It is an object of this invention to simplify the structure of such a bearing and to provide one form of the same comprising only three parts, a housing, a bearing plate and a roller.

It is a further object of the invention to provide the bearing roller with integral means for locking the same to the housing and also to provide improved means for retaining the bearing plate in the housing.

These and other objects and advantages of the invention will be apparent from the following description made in connection with the accompanying drawings, in which like reference characters refer to the same parts throughout the different views, and in which

Fig. 1 is a top plan view of the bearing assembled;

Fig. 2 is a view in side elevation of the same, a portion thereof being shown in section and different positions of the roller being indicated by dotted lines;

Fig. 3 is a vertical central section of such a bearing;

Fig. 4 is a partial top plan view of the bearing plate; and

Fig. 5 is a section of a modified form of the roller.

Referring to the drawings, the bearing as a whole comprises a housing member *a*, a bearing plate *b* and a roller *c*. The housing *a* is of substantially rectangular form and comprises substantially parallel side walls connected by webs at each end forming the end walls of the housing which webs are curved inwardly on a curve having a radius substantially the same as the bearing roller. It will be noted that the said webs are pro-

vided with openings below the top portion 55 thereof and that side webs *a*¹ extend from the top of said webs at each side thereof to the base portion of the housing. At one side the housing is provided with a projecting portion in which is formed a recess or 60 slot *a*², the top of which as will be seen from Fig. 2, slopes downwardly toward the center of the housing at an incline substantially the same as that of the surface of the bearing plate to be later described. The 65 recess *a*² extends toward each end of the housing and at the center thereof extends downwardly to the bottom thereof. At its other side the housing is shown as having a strengthening ledge or rib *a*³ along its top 70 surface and securing lugs *a*⁴ provided with suitable bosses and bolt holes are shown at each corner of the housing. Extending downwardly and inwardly at each end of the bottom portion of the housing are centrally located lugs *a*⁵.

The bearing plate *b* is adapted to be disposed in the housing with its bottom surface flush with the bottom surface of the housing and is provided on its top surface with downwardly inclined bearing surfaces converging toward the center of the housing, the ends of the plate being beveled downwardly and outwardly, as clearly shown in Fig. 2. The plate is formed at each end with a central 85 notch *b*¹, the inner edge of which is inclined downwardly and inwardly and the plate is formed on one side with a projecting longitudinally extending lug *b*² adapted to be received in the recess *a*² of the housing. 90 It will be noted that the end walls of the housing are inclined outwardly and downwardly at *a*⁶ and the bearing plate *b* is arranged to be inserted into the housing from below. The lugs *a*⁵ will then enter the 95 notches *b*¹ and are adapted to be then bent inwardly adjacent the inclined surfaces of the notches so that the plate is held from dropping from the housing and the same will also be prevented from rising by contact with the end portions *a*⁶ of the housing. 100 The bearing plate is preferably made of hardened steel and will preferably be a steel casting although the same might also be forged. The bearing plate is suitably 105 cored and ribbed on its undersurface, as shown in Figs. 3 and 4.

The roller *c* is of general cylindrical

shape and rolls on top of the bearing plate *b* with its ends parallel and in close proximity to the undersurface of the side walls of the housing. The roller is suitably cored to 5 eliminate excessive weight and in accordance with this invention, the same is provided with a central projecting hub *c*¹ adapted to be disposed in the recess *a*² of the housing.

The roller is made to run in close contact 10 with the side walls of the housing so as to get all possible wearing surface on the bearing plate *b*, and by having one side of the housing formed with a continuous unbroken surface, an increased bearing and wearing 15 surface for that end of the roller is obtained. When the roller is moving in operation the projection *c*¹ will move into the ends of the recess *a*² as the roller travels to one end or the other of the housing, and the travel of 20 the roller is limited by the same striking the end walls of the housing. The roller returns to its central position by gravity on account of the inclined surface of the bearing plate *b* and the same is locked in the housing or 25 prevented from rising therefrom by the engagement of the hub or projection *c*¹ with the top of the recess *a*².

In Fig. 5, a slightly modified form of 30 roller is shown in which the roller *d* is provided with a central core, as in the other drawings, but is bored at each end to receive a separate pin *d*¹ which is preferably welded to the roller or has to be substantially integral therewith, this preferably being done 35 by spot welding with acetylene.

In assembling the device the roller is dropped into the housing from the bottom with the hub *c*¹ in the recess *a*² and the plate *b* is then inserted in the bottom and the lugs 40 *a*⁵ bent into contact therewith.

The operation of the device has already 45 been indicated and it is thought will be clearly understood. It will be noted that the hub or projection *c*¹ does not bear on the housing when the roller travels on the bearing plate but merely comes into contact with the top of the ledge in the recess *a*² when the roller tends to lift.

It will thus be seen that applicant has 50 provided an extremely simple and efficient side bearing and one comprising very few parts. These parts can be ruggedly made and easily assembled and require no separable fastenings for holding the same in assembled position.

It will, of course, be understood, that various 55 changes may be made in the form, details and arrangement of the device without departing from the scope of applicant's invention, which, generally stated, consists in the matter shown and described and set forth in the appended claims.

What is claimed is:

1. A side bearing for railway cars having 60 in combination, a housing having inside

walls with inside flat substantially parallel surfaces, a bearing plate in the bottom of said housing, a bearing roller supported on said plate, said roller having one end formed as an uninterrupted plane surface arranged 70 to bear against the wall of the housing, and means on the other end of the roller co-operating with the housing to prevent the roller lifting therefrom.

2. A side bearing for railway cars having 75 in combination a housing having substantially straight vertical parallel side walls and curved end walls, one of said walls having a substantially T-shaped recess formed therein the upper arms thereof extending toward each end thereof and entirely closed at the top, a bearing plate secured in said housing and a substantially cylindrical roller disposed in said housing having one plane uninterrupted end surface adapted to bear 80 against one side wall of said housing supported upon said plate and having a central projecting hub at its other end adapted to travel in said recess whereby said roller is prevented from rising from the housing. 90

3. A side bearing for railway cars having 95 in combination a housing having an opening through the bottom thereof, and end portion extending from said opening, a bearing plate adapted to be disposed in said opening and having end surfaces adapted to contact with said projecting portions to limit the inward movement of said plate, inwardly extending surfaces, said projecting portions of the housing having lugs adapted to be disposed in said recesses in contact with said last mentioned surfaces of the plate to retain the plate in the housing. 100

4. A side bearing for railway cars having 105 in combination a housing having an opening in the bottom thereof, a bearing plate having notched ends adapted to be disposed in the bottom of said housing, said housing having lugs projecting at the bottom thereof adapted to be disposed in said notches in contact with the plate to retain said plate in the housing. 110

5. A side bearing for railway cars having 115 in combination a housing having an opening in the bottom thereof, a plate adapted to be disposed in said opening having a notch in each end, said housing being provided with downwardly extending lugs at each end thereof adapted to be received in said notches and disposed in contact with said edge of the plate to hold the same in said housing. 120

6. A side bearing for railway cars having 125 in combination a housing having an opening in the bottom thereof and portions extending at each end of said opening, a bearing plate adapted to be disposed in said opening having a top surface adapted to contact with said projecting portions of the housing to limit the inward movement of said plate and 130

also having a notch at each end with an inwardly projecting surface, said housing having lugs adapted to be received in said notches and disposed in contact with said inner inclined surfaces thereof to retain said plate in the housing.

7. A device of the class described having in combination a housing having vertical fixed side walls, a roller disposed in said 10 housing and having one plane end parallel to the adjacent housing wall and adapted to contact therewith, said wall having a continuous unbroken surface affording a large bearing surface for said roller.

15 8. The structure set forth in claim 7, and the other side wall having means co-operating with said roller to retain the same in said housing.

9. The structure set forth in claim 7, 20 and the other side wall of said housing hav-

ing a recess therein, and integral means on said roller adapted to be disposed in said recess to retain the roller in said housing.

10. A device of the class described having in combination a housing, a bearing plate 25 therein and a bearing roller movably mounted therein, said roller being mounted for free rolling translation longitudinally of said plate and housing and having centrally axially disposed integral means thereon 30 adapted to engage with said housing to retain the roller therein.

In testimony whereof we affix our signatures in presence of two witnesses.

LEE W. BARBER.
EDWIN W. WEBB.
